UNITED STATES PATENT OFFICE

CHARLES FISHER, OF NEW YORK, AND CHARLES D. FISHER, OF BEACON, NEW YORK;
L. STEWART GATTER, EXECUTOR OF SAID CHARLES FISHER, DECEASED

EDUCATIONAL TOY AND DISPLAY DEVICE

Application filed September 12, 1925. Serial No. 55,960.

This invention relates particularly to a display device which is adapted to be used by children, as well as by adults. The device is in the nature of a toy picture-displaying device, but may be usefully employed for educational purposes.

The primary object is to provide a simple and inexpensive device of this character which can be readily operated by a child, and which permits of the ready removability of the endless display strip, or film, and the insertion of a fresh film.

A further object is to provide a device of this character which is so constructed as to facilitate the making of copies of designs, or pictures, or the like, appearing on the display strip, with which the machine is provided.

The invention comprises, in the preferred construction, a small rectangular cabinet, the main portion of which serves as a receptacle for the film, or flexible strip, which forms in loops, or folds, therein; a pair of friction-rolls located in the upper portion of the cabinet serving to feed the film, the main roll being equipped with a crank; an inclined window at the upper front portion of the cabinet; and a film-guide which may serve also as a lamp-housing, or reflector, interposed between said window and the film-feeding rolls, said housing being open at its front end to permit the rays of light to pass through the film, or picture-strip, as the latter is fed past the window.

The invention is illustrated in its preferred embodiment in the accompanying drawings, in which—

Fig. 1 represents a broken front elevational view of our improved display device; Fig. 2, a vertical sectional view taken as indicated at line 2 of Fig. 1; Fig. 3, a plan sectional view taken as indicated at line 3—3 of Fig. 2; Fig. 4, a plan section taken as indicated at line 4—4 of Fig. 2; Fig. 5, a front perspective view of the lamp-housing, or shield, employed; Fig. 6, a broken sectional view taken as indicated at line 6 of Fig. 4, this view illustrating a device for preventing reverse rotation of the main feed-roller; Fig. 7, a fragmentary view of the ends of the picture-strip connected together; Fig. 8, a broken plan

view illustrating the manner in which the picture-strip may be mounted on a roll when it is not in use; Fig. 9, a fragmentary edge view of the end portions of the strip; Fig. 10, a broken sectional view of the storage-roll, the section being taken as indicated at line 10 of Fig. 8; and Fig. 11, a transverse sectional view of the storage-roll taken as indicated at line 11 of Fig. 8.

In the preferred construction which is illustrated, A designates a cabinet; B, a combined lamp-housing and film-guide which is mounted in the upper front portion of the cabinet; C, a main friction feed-roll which is mounted back of the device B and with which co-acts a spring-held idle-roll C'; and D, an endless picture-strip, which, for brevity, may be termed an endless strip.

The cabinet A may be of any suitable size and construction. It may, for example, be a cabinet having a height of about ten inches, a width of about six inches, and a depth from front to rear of about eight inches; and, preferably, the cabinet is provided with a rear wall 1, side walls 1^a; a bottom wall 1^b; a top wall 1^c; and a lower front wall section 1^d which fits freely between the front portions of the side walls and is hinged to the front portion of the bottom wall as indicated at 2. Preferably, also, the upper front corner of the cabinet is cut away; and the lower front wall section 1^d has secured to its upper margin a metal plate 3 which sets in an inclined position and serves as a window frame. The plate 3 may be stamped from sheet-metal and provided with an opening 4 of suitable dimensions.

At the margins of this opening, the metal is stamped forwardly, as indicated at 4^a; and in the marginal recess thus provided, there is fitted a plate 5 of transparent material, preferably of celluloid. It is preferred to employ celluloid and provide the sheet, or plate, with a series of marginal perforations 5^a through which pass clenching lugs 6 which are formed integrally with the plate 3. These clenching lugs pass rearwardly through the sheet of celluloid and are bent outwardly at the rear surface of the celluloid sheet.

The lower marginal portion of the metal

plate 3 is provided with a vertical attaching portion 3^a which is secured as by means of screws 7 to the upper margin of the door-section 1^d. At its upper edge, the plate 3 is provided with a finger piece 3^b which has a perforation which snaps over a stud, or nail head, 8, with which the top wall of the cabinet is provided at its front central portion. The lateral margins of the metal plate 3 overlap the beveled front edges of the side walls of the cabinet, and give a finished appearance to the cabinet.

The means for feeding the film is exceedingly simple and highly effective. Such means comprises the friction feed-roll C and the co-acting spring-pressed idle-roll C'. The roll C preferably comprises a cylindrical wooden piece 9 and a pair of friction sleeves 10, preferably of rubber, fitted on the member 9. One end of the member 9 is provided with a bore 9^a which serves as a bearing for a nail, or trunnion, 11, which extends through one of the side walls of the cabinet. The other end of the member 9 is provided with a bore in which is fitted a plug-like trunnion 12 whose outer end is journalled in the corresponding side wall of the cabinet. The member 12 is provided with a tapped bore which receives the threaded shank of a crank 13. The screw connection at this point employs a right-handed thread, the connection being sufficiently loose to allow the crank to unturn in the event an effort is made to work the crank in a direction reverse 35 to that indicated by the arrow in Fig. 2.

The idle-roll C' is provided with a shaft 14 which is journalled in a bearing 15 with which a leaf spring 16 is equipped. The end portions of the shaft 14 are provided with 40 enlargements 14^a which co-act with the rubber sleeves 10 of the main feed-roll C.

The front end of the leaf spring 16 is secured by screws 17 to the underside of the front portion of the cabinet top 1^c. The spring has a rearward and downward inclination, and has an extension 16^a which projects to a point near the rear wall of the cabinet.

The combination film-guide and lamp-housing B preferably comprises a sheet-metal member having a rear wall 18, a top wall 19, and a bottom wall 20. The walls 19 and 20 are forwardly divergent, and the upper wall is shorter than the lower wall. The housing 50 may be formed from a strip of sheet-metal which provides the rear corners 21 and 22. These portions are supported by nails 23 which extend inwardly from the side-walls. The metal at the front edge of the upper wall 55 19 is formed to provide a bead 19^a; and the metal at the front edge of the wall 20 is formed to provide a bead 20^a. The member B is supported at these points by nails 24 which extend through the side walls of the 60 cabinet and into the rolls, or beads, 19^a and 65 20^a, as will be best understood from Fig. 3.

It will be understood that the sheet-metal lamp-housing B is without end walls, except as end walls are provided by the side walls of the cabinet. One of the side walls is provided with an opening 25 in which is fitted a lamp-socket 26 which supports a lamp-bulb 27. The lamp is thus located within the housing B. The housing may be formed of aluminum, tin, or other bright metal, so that it will serve as a reflector.

As will be understood from Figs. 2 and 4. an intermediate portion of the metal of the wall 18 of the member B is sheared and virtually forms an extension 28 of the lower wall 20. This extension 28 projects into the space between the sleeves 10 of the feed-roll C and serves as a guard to prevent the film from entering the space between the feed-roll C and the wall 18.

It will be noted from Fig. 2 that the film D extends in an upwardly and rearwardly inclined position adjacent the window and is supported at the upper and lower edges of the window by the rolls 19^a and 20^a which thus serve as guides for the film. The upper and lower walls 19 and 20 also serve as guide surfaces for the film. The width of the film is substantially equal to the interior width of the cabinet, so that the edges of the film are at all times in guiding contact with the side walls of the cabinet.

The film preferably is of good quality paper which is easily flexed, but which possesses the requisite degree of stiffness and resilience to enable the friction feed-rolls to force the issuing strip to form in a series of folds at the rear upper portion of the cabinet and tend to work the folds, or loops, downwardly and forwardly, so the strip will be drawn readily over the guide-members 20^a and 19^a and be presented as a transparent, or translucent medium back of the window so that rays of light from the lamp 27 can project through the film, and thus cause the pictorial illustrations, reading matter, etc., carried by the film, to be seen clearly by an observer viewing the film through the window.

The film may have pictures, designs, illustrated stories, etc. arranged serially thereon; or any desired printed matter may be carried by the film.

It is preferred to extend a small rod, or stiff wire, 29 across the front portion of the cabinet just back of the door-section 1^d and a short distance beneath the guide-bead 20^a and to have the film pass back of the member 29 and in front of the member 20^a; the disposition of these members being such as to produce a curve in the film and cause a suitable degree of friction at a point where the film passes to the observation area. The folds of the film also press the film against the lower and front walls of the cabinet in such a way as to produce a certain amount of friction. This

is found to be sufficient for the purpose of tensioning the film throughout the area which is exposed to view, it being understood that the film is drawn upward and rearwardly by the friction-feed device.

As explained above, the crank 13 has a threaded shank which engages a threaded socket with which the trunnion 12 is provided. By this means, when the crank is turned clockwise, the roll C will be turned in the direction indicated by the arrow in Fig. 2. An anti-retraction device 30 is employed to prevent the roller C from being returned in a reverse direction. This device preferably comprises a wooden block 31 which is pivotally mounted on a screw, or stud, 32 which projects inwardly from one side wall of the cabinet and which has its free end bearing against the wooden shaft 9 of the friction feed-roll C; and a wire spring 33 having one end anchored in the block 31, as indicated at 33^a, and having the free end bearing beneath a shoulder 34 with which the rear wall of the member B is provided. The block 31 inclines downwardly and rearwardly, so that the upper corner portion 31^a projects somewhat over the wooden shaft 9. The spring 33 is under light tension, tending to swing the free end of the block downwardly. However, the feed-roll C can be rotated freely clockwise by means of the crank 13. If an effort be made to operate machine in a reverse direction, the block 31 will wedge between the pivot 32 and the wooden shaft 9, and the crank will unscrew from the trunnion, or socket, 12. The block 31 is housed in the rear portion of the lamp-housing B and the free extremity of the block extends through a slot, or recess, 34^a whose upper wall affords the shoulder 34.

The friction sleeves 10 on the wooden shaft 9 preferably are of comparatively soft rubber, so that they are slightly yielding.

The flexible band, or film, D preferably has its ends connected in the manner illustrated in Figs. 9 and 7. One end of the strip is cut so as to form a reduced central portion which is folded back upon itself to form a loop 35 and has its extremity pasted to the body of the strip as indicated at 35^a. The other end of the strip has its central portion cut away, thus leaving near the lateral margins tabs, or ears, which are folded back upon the body of the strip to form loops 36, the extremities being pasted to the body of the strip, as indicated at 36^a. The loop 35 fits freely between the loops 36 and the parts are connected by a thin, narrow, flexible bar, 37, which extends through the loops.

As a means for storing films which may be used in the improved machine, it is preferred to provide a paste-board tube 38 which has portions of its circumference cut and pressed inwardly, as indicated at 38^a, thus

leaving a central circumferential portion 38^b. The end of the strip which is provided with the loops 36 may be secured to the core, or roll, 38, by placing the end of the strip on the roll with the loops 36 flanking the depressions 38^a. One of the flexible bars 37 may then be passed through a loop 36, then through the loop 38^b of the core, and then through the other loop 36 of the strip. The strip may then be wound upon the core and secured by rubber, or in any desired manner.

It will be understood that the rolls of films adapted for use in the machine may thus be provided so that the owner of the machine may be supplied with any desired number of different subjects on interchangeable films which can be used in the machine.

The celluloid plate 5 preferably is of suitable thickness and stiffness to enable it to serve as a support for a sheet of paper, or other transparent material, when employed for copying purposes. Such a sheet may be placed upon the inclined window, and a child may trace thereon the figures, or illustrations, which appear on the film, visible through the sheet of paper. Thus, the improved displaying device may be usefully employed for encouraging a child to learn to make pictures.

In introducing a film into the machine, the front wall of the cabinet which comprises the door-section 1^a and the window carried thereby may be thrown forwardly about the hinge 2, thus leaving the entire front of the cabinet open. The film may then be fed rearwardly over the guide 19^a and between the feed-rolls. The feed-rolls may then be operated to feed the film into the cabinet, and the ends of the film may be joined together in a manner which will be obvious from the description heretofore given. After the film has been properly introduced, the door of the cabinet may be closed, and the machine is then ready for operation.

The improved machine is of exceedingly simple construction, may be manufactured at moderate cost, and may be supplied to the public at a popular price. The machine is thoroughly adapted to its purpose and is simple and reliable in operation.

While it is preferred to mount a lamp in the film-guide and guard B, the lamp may be omitted, if desired. Any suitable method of lighting the film, either by transmitted or by reflected light may be employed, or reflected daylight will answer the purpose. It is important, however, that the film be properly guided and that provision be made for so guarding the motive device that the folds of the film cannot enter between the rolls, or between the member B and the rolls.

The foregoing detailed description has been given for clearness of understanding only and no unnecessary limitations should be understood therefrom, but the appended

claims should be construed as broadly as permissible in view of the prior art.

What we regard as new, and desire to secure by Letters Patent, is:

5 1. In a machine of the character set forth, the combination of a cabinet provided at its upper front portion with a window, a film-guide in the upper portion of said cabinet and open to said window and projecting rearwardly therefrom and affording an upper 10 film-confining wall, the space below said wall serving to receive the film folds, an endless film passing between said film-guide and said window, and a friction-feed device back of said film-guide serving to draw the film through the passage between said window and said film-guide and force it to form in folds below the film-guide, the lower walls of said cabinet co-operating with a wall of the film-guide to confine the film, whereby folds will be formed in the film as the film issues from said friction-feed device.

2. In a machine of the character set forth, the combination of a cabinet provided at its 25 upper front portion with a window, a lamp-housing supported in the upper front portion of said cabinet and open to said window and projecting rearwardly therefrom and affording an upper overhanging film-confining wall, an endless film passing between said lamp-housing and said window, and a friction-feed device back of and adjacent the rear portion of said lamp-housing serving to draw the film through the passage between 30 said window and said lamp-housing and form it into folds as it issues from the friction-feed device adjacent the rear wall of the cabinet, the space below the lamp-housing and friction-feed device serving as a container for 35 the folded film.

3. In a machine of the character set forth, the combination of a cabinet provided at its 45 upper front portion with a rearwardly and upwardly inclined window, a lamp supported in said cabinet back of said window, film-guiding means disposed adjacent the window but spaced therefrom and projecting rearwardly from said window and affording an upper overhanging film-confining wall, an 50 endless film passing between said window and said film-guiding means, and a friction-feed device serving to draw the film through the space between said window and said film-guiding means and discharge it in folds, the 55 lower portion of the cabinet serving as a container for the folded film and the walls of the lower portion of the cabinet serving to confine the folds of the film.

60 4. In a machine of the character set forth, the combination of a cabinet having its upper front portion provided with an upwardly and rearwardly inclined window, a combined lamp-housing and reflector disposed back of 65 said window and projecting rearwardly therefrom and affording an upper overhang-

ing film-confining wall and adapted to emit light through the window, a lamp in said housing, a friction-feed device supported in the upper portion of the cabinet back of said housing, and an endless film passing through 70 the space between said window and said housing and through said friction-feed device, said friction-feed device serving to force the film to form in folds which occupy the space in the cabinet beneath said housing and said friction-feed device.

75 5. A machine of the character set forth in claim 1 characterized by a friction-feed device disposed back of the film-guide and comprising only a main friction-roll journaled 80 in the side walls of the cabinet and a co-operating spring-held friction-roll.

85 6. A machine of the character set forth in claim 1 characterized by the friction-feed device comprising only a main friction-feed roll journaled in the side walls of the cabinet, a co-operating spring-held friction-roll, and a crank connected with one end of the main friction-roll so as to impart rotation thereto in one direction only.

90 7. A machine of the character set forth in claim 1 characterized by a main friction-roll equipped with yielding rubber sleeves and a co-operating spring-held idle friction-roll adapted to press the film against said sleeves.

95 8. A machine of the character set forth in claim 1 in which the friction-feed device is characterized by a main friction-roll disposed back of the film-guide and a co-operating idle friction-roll is mounted on a leaf-spring which is secured at its front end to the upper front portion of the cabinet, a passage being afforded between said leaf-spring and the upper wall of the film-guide through 100 which the film may pass.

105 9. A machine of the character set forth in claim 1 characterized by the window being inclined rearwardly and upwardly and the film-guide being provided with forwardly divergent top and bottom walls with rounded 110 surfaces at the front ends of said wall serving as film-guides.

115 10. A machine of the character set forth in claim 1 characterized by the film-guide constituting a lamp-housing formed of sheet-metal and presenting an upper wall, a rear wall and a bottom wall, said lamp-housing extending between the side walls of the cabinet which thus afford the side walls of the lamp-housing.

120 11. A machine of the character set forth in claim 1 characterized by the film-guide having inclined upper and bottom walls and characterized further by the friction-feed device comprising the main friction-feed-roll 125 and a co-operating friction-feed idle roll carried by an inclined spring secured to the upper front portion of the cabinet and having an extension projecting to a point near the rear wall of the cabinet.

12. A machine comprising a cabinet provided at its upper front portion with an inclined window, a combined lamp-housing and reflector disposed back of said window, a lamp in said housing, said lamp-housing having an upwardly and forwardly inclined upper wall and a downwardly and forwardly inclined lower wall, film-guides at the front ends of said walls, an endless film passing between the window and said guides and having folds occupying the space in said cabinet below said housing, and a friction-feed device comprising a main friction-feed roll journaled in the side walls of the cabinet, a self-releasing crank adapted to impart rotation in one direction only to said feed-roll, and a co-operating spring-held friction-roll disposed above the main feed-roll, said film extending between said rolls.

13. A machine of the character set forth in claim 12 characterized by a guard device adapted to prevent the film from entering the space between the rear portion of said housing and said main feed roll.

14. A machine of the character set forth in claim 12 characterized by film-flexing friction means at the lower front portion of said housing.

15. A machine of the character set forth consisting of a cabinet provided at its upper front portion with an upwardly and rearwardly inclined window, a film-guide disposed back of said window and consisting of a top wall, a bottom wall and a connecting rear web, said film-guide being open at its front and at its ends, connections between the ends of said film-guide and the side walls of the cabinet, and a friction-feed device mounted in the rear upper portion of said cabinet and serving as the sole means of drawing a film upwardly past the window, back over said film-guide and downwardly into the lower part of the cabinet, said friction-feed device consisting only of a main feed-roll and a co-operating spring-held friction roll.

16. A machine of the character set forth consisting of a cabinet provided at its upper front portion with a window, a lamp-housing disposed back of said window and consisting of a top wall, a bottom wall and a connecting rear web, said lamp-housing being open at its front and at its ends, connections between the ends of said lamp-housing and the side walls of the cabinet, a lamp mounted in said housing, a friction-feed device mounted in the rear upper portion of said cabinet and serving as the sole actuating means, a film having a portion extending between said window and said housing and through said friction-feed device and having folds confined in the lower portion of the cabinet in the space beneath said lamp-housing and friction-feed device, and means for turning said friction-feed device in such direction as to draw the film upwardly past the window and force it to form

in folds adjacent the rear wall of the cabinet back of the friction-feed device.

17. A machine of the character set forth, comprising a cabinet having a hinged front wall equipped at its upper portion with an inclined window, a reflector mounted between the side-walls of the cabinet back of said window, a lamp in said reflector, a friction-feed device back of said reflector, and an endless film passing between said window and said reflector and over the top of said reflector to said friction-feed device, said film having folds occupying the space of the cabinet beneath said reflector and said friction-feed device.

18. A machine of the character set forth, comprising a cabinet having a hinged front wall comprising a window at its upper portion, a lamp-socket mounted in a side wall of said cabinet back of said window, a reflector mounted between the side walls of said cabinet, a lamp mounted in said socket and disposed within said reflector, a friction-feed device mounted in the upper portion of said cabinet back of said reflector and having a shaft extending through a side wall of the cabinet, an endless film passing between said window and said reflector and thence through said friction-feed device, and means for turning said shaft in such direction only as to draw the film upwardly past said window and force it to form in folds and occupy the space of the cabinet beneath said reflector and said friction-feed device.

19. A machine of the character set forth, comprising a cabinet provided at its upper front portion with an upwardly and rearwardly inclined window which may serve as a support for an exteriorly placed copy sheet, a reflector spaced adjacent said window, film-guiding means adjacent said window over which a film may be stretched adjacent the window, a lamp in said reflector, an endless film supported on said film-guiding means, and film-feeding means mounted in the rear upper portion of said cabinet and adapted to draw a film past said window, said film-feeding means serving to cause said film to issue and form in folds which occupy the lower portion of said cabinet.

20. A machine of the character set forth in claim 1 in which the friction-feed device is characterized by a main friction-roll, a handle adapted to turn said roll in one direction only, and a spring-held wedge device adapted to prevent retrograde movement of said roll.

CHARLES FISHER.
CHARLES D. FISHER.
